UNITED STATES PATENT OFFICE

WILLIAM A. MILLS, OF PORT CHESTER, NEW YORK, ASSIGNOR, BY DIRECT AND MESNE ASSIGNMENTS TO FORAN BOILER COMPANY, INC., A CORPORATION OF NEW JERSEY

STEAM GENERATOR OR BOILER

Application filed December 19, 1930. Serial No. 503,467.

This invention relates to steam generators or boilers. In one of its aspects, the invention relates to boiler tubes for such generators and the arrangement thereof. In another of its aspects, the invention relates to improvements in the various component elements of the boiler.

One object of the invention is to provide a boiler of increased efficiency and durability.

10 To this end, a rapid circulation of the steam from its point of generation to the steam dome is effected. A plurality of circulating headers extend between the water base and the steam dome, each of which circulating headers carries a plurality of boiler tubes, extending across the heating chamber, whereby the steam generated in each tube travels only the return distance in that tube to the circulating header and up the header to the steam dome.

20 The invention also seeks a disposition of boiler tubes such as to permit an even distribution of the gases and other products of combustion and to prevent the formation of a bridge of carbon or soot between adjacent tubes which would impede the flow of gases and insulate the tubes against the heat.

Still another object of the invention is to provide a boiler which can be constructed and maintained at a minimum expense.

30 It is also an object of the invention to provide a boiler which is practical from the standpoint of ease and cheapness of manufacture and convenience in installation and use.

35 These and other objects of the invention and the means for their attainment will be more apparent from the following detailed description, taken in connection with the accompanying drawings illustrating various embodiments by which the invention may be realized, and in which:

Figure 1 is a view, in side elevation, showing a boiler in accordance with this invention, one of the circulating headers, and certain 45 of the boiler tubes being broken away in the interest of clearness;

Figure 2 is a view in front elevation showing the boiler of Figure 1;

Figure 3 is a transverse sectional view taken 50 in the plane indicated by the line 3—3 of Fig-

ure 2 and showing the disposition of a companion pair of headers upon opposite sides of the boiler and the relation of the tubes thereof;

Figure 4 is a fragmentary view showing a 55 modified disposition of boiler tubes;

Figure 5 is a sectional view on the line 5—5 of Figure 4.

Figure 6 shows still another arrangement 60 of boiler tubes;

Figure 7 is a view in side elevation showing the boiler tubes of Figure 6;

Figure 8 is a sectional view showing headers on opposite sides provided with still another disposition of boiler tubes; and 65

Figure 9 is a fragmentary view of one header of Figure 8, looking toward the end of the tubes on line 9—9 of Figure 8.

The boiler embodying this invention is shown as having side members 10 which are 70 joined by the rear portion 11 to form a three sided substantially rectangular water base. This water base, of course, may rest upon any form of base and be elevated to any degree so as to be adaptable to either 75 a coal fired boiler or an oil or gas burner. The sides 10 are L-shaped, in part, in vertical cross section, that is, while the base as a whole is substantially rectangular in vertical cross section, the sides 10, along the inside, 80 are provided, respectively, with upwardly extending portions 12. These upper parts serve as connecting portions or manifolds for the circulating headers 16, the parts 12, 85 extending rearwardly from a point just in rear of the front return pipes 17, to preferably a point just in front of the rear return pipes. At each corner, there is mounted upon the base, a return pipe 17, preferably rectangular or square in horizontal cross-section, 90

which opens into the ends of the side members 10 and communicates with and supports at the top a steam dome 18, also preferably rectangular, which steam dome has a downwardly extending portion 20 disposed between the return pipes 17 and extending the entire front to rear dimension of the manifold portions 12 of the base, so as to carry as much water as possible in the dome to prevent too rapid cooling of the water. If de- 105

sired, the pairs of front and rear return pipes may be in communication, respectively, as by casting them in one piece, respectively, with a circulating hollow wall member which serves as the front and back walls of the boiler. In Figures 1 and 2 such a unitary water return wall is shown at 19.

A plurality of circulating headers 15, 16, are shown arranged along each side of the boiler between the front and rear return pipes 17. In the illustrated embodiment five such circulating headers are shown.

The circulating headers 15, 16, communicate with the upwardly extending portions 12 of the base sides 10 and with the downwardly depending central portion 20 of the dome 18. Preferably nipples 14 connect the headers to the respective parts 12 and 20.

The circulating headers 15 along one side 20 are not directly opposite the headers 16 on the other side, but are offset by almost half their width, as shown clearly in Figure 3. The return pipes 17 may be either cylindrical or rectangular in horizontal cross section but in the preferred embodiment, both return pipes and headers are shown as rectangular in cross section.

In the modification according to Figures 1 to 3, each vertical header 15, 16, has connected thereto a row of generally horizontally disposed U-shaped tubes, 21, 22 and 23, 24 respectively, which extend from one header almost to the opposite one. The legs of each boiler tube lie in parallel planes, the planes being at an angle to the horizontal as shown in Figure 1, and the tubes 21, 22 on the header 15 on one side are so spaced that the boiler tubes 23, 24 on the opposite header 16 extend therebetween, Figures 1 and 3. Being offset, one leg, say 24, of a tube lies substantially in a vertical plane passing between the pair of legs 21, 22 of the opposite tube and they are so shaped that there is ample space for the circulation of flue gases therebetween, the tubes being spaced from one another sufficiently to avoid an accumulation of soot which would bridge adjacent tubes and form an insulation against the heat. As shown in Figure 2, there are seven boiler tubes on each header.

In the modification illustrated in Figures 4 and 5, the headers are so disposed that a header 26 upon one side is located opposite the space between adjacent headers 27, 27 on the opposite side, and the U-shaped tubes 28, 29 lie in vertical planes in two series on each header. Thus two series of four tubes each may be disposed on the headers with the tubes 28 of one series, being offset with respect to the tubes 29 of the other series as shown, so as to have a tube communicating with substantially each level in the header. This construction affords eight tubes on each header as compared with the disposition of tubes

shown in Figures 1 to 3 wherein each header carries seven tubes.

In the modification shown in Figures 6 and 7, substantially the same effect, as in the modification of Figures 4 and 5, is obtained by providing two reversely bent tubes 31, 34 in each of the two series on each header. Each of these reversely bent tubes takes the place of two tubes but instead of having both legs of each tube in communication with a header 35, the adjacent legs 32, 33 are joined as at 36 so that the fluid passes through four legs before again entering a header. Here again the legs of each tube of a series are offset, vertically, with respect to the legs of the adjacent series and the tubes extend across the fire box, almost to the opposite headers.

In the modification illustrated in Figures 8 and 9, the tubes are not of U or hairpin shape, but there is a tube 42 mounted on the header 43 in place of each leg of the U-shaped tube of the modification of Figures 1-3. Thus, instead of a series of seven U-shaped tubes, this modification provides sixteen straight tubes, eight in each of two vertical series, the tubes 42 of one series being offset, vertically, with respect to the tubes 44 of the adjacent series. Also, as before, the tubes extend substantially across the boiler.

The water from the boiler fills the water base 10 and rises into the vertical headers and fills the return pipes and the steam dome to a level above the top of the tubes, as indicated at W in Figure 2. The water in the tubes is converted into steam from the heat of the products of combustion from the fire. The steam thus generated passes through but a single tube into the headers and from thence it passes through the nipples into the steam dome, the water of condensation, etc., returning from the steam dome to the water base through the return pipes 17 or wall 19. It will be obvious that the travel of the steam from its point of generation to the dome is relatively short since the steam only traverses one tube.

The boiler tubes extending, as they do, practically across the boiler receive the maximum of heat and being evenly spaced afford a free flow of hot gases in contact with every portion thereof.

Each unit or section of the boiler consisting of a header and its tubes mounted thereon, may be cut out of service in case of accident without interfering with the service of the remaining units of the boiler, it being only necessary to disconnect the header from the steam dome and water base and plug up the holes in the parts 12 and 20 from which the nipples have been removed. The unitary front and rear return walls 17, 19 close the ends of the boiler. At the sides, the spaces between the circulating headers may be closed by removable plates 46. Upon removal of such plates the interior of the boiler is ex-

posed for cleaning. The disposition of tubes on spaced circulating headers permits ready cleaning of the tubes by a brush inserted through the side where the plates have been removed.

Various modifications will occur to those skilled in the art in the configuration and disposition of the component elements going to make up the boiler as a whole and no limitation is intended by the phrasedology in the foregoing description or illustrations in the accompanying drawings, except as indicated in the appended claims.

What is claimed is:

ing with the return pipes, a plurality of vertical headers disposed along each side of the boiler between the return pipes, connections between the headers and the steam dome and water base, respectively, said headers upon one side being offset with respect to the headers on the other side, a series of boiler tubes carried with each header and extending across the boiler substantially to the opposite header, and the boiler tubes of one header extending between the boiler tubes of the opposite header.

5. In a steam generator or boiler, in combination, a substantially rectangular three-sided water base whereof the sides are formed with raised portions, return pipes disposed at the four corners of the water base and communicating therewith, a substantially rectangular steam dome supported by and communicating with the return pipes and having a centrally disposed depending portion, a plurality of vertical headers disposed along each side of the boiler between the return pipes, connections between the raised portions of the water base and the headers, respectively, connections between the depending portion of the dome and the headers, respectively, and a series of substantially horizontally disposed boiler tubes carried with each header, and the boiler tubes of one header extending toward the opposite header and between the boiler tubes of the opposite header. 80 85 90 95 100

6. In a steam generator or boiler, in combination, a substantially rectangular three-sided water base whereof the sides are formed with raised portions serving as manifolds, respectively, for headers on that side, return pipes disposed at the four corners of the water base and communicating therewith, a substantially rectangular steam dome supported by and communicating with the return pipes and having a centrally disposed depending portion, a plurality of vertical headers disposed along each side of the boiler between the return pipes, connections between the raised portions of the water base and the headers, respectively, connections between the depending portion of the steam dome and the headers, respectively, said headers upon one side being offset with respect to the headers on the other side, a series of substantially horizontally extending boiler tubes carried with each header and extending across the fire pot and the boiler tubes of one header extending between the boiler tubes of the opposite header. 105 110 115 120 125

7. In a steam generator or boiler, in combination, a water base, a steam dome, a plurality of spaced vertical circulating headers disposed along each side of the boiler and communicating with the water base and the steam dome, respectively, a header on one side being opposite the space between adjacent headers on the other side, two vertical series of boiler tubes carried with each header and 130

extending across the boiler, the boiler tubes of one header extending in the space between the groups of boiler tubes of the adjacent headers on the opposite side.

8. In a steam generator or boiler, in combination, a water base, a steam dome, a plurality of spaced vertical circulating headers disposed along each side of the boiler and connecting the water base and the dome, a header on one side being opposite the space between adjacent headers on the other side, and boiler tubes carried with each header and extending across the boiler, the boiler tubes of one header extending between the boiler tubes of the opposite adjacent headers.

9. In a steam generator or boiler, in combination, a water base, a steam dome, a plurality of spaced vertical circulating headers disposed along each side of the boiler and connecting the water base and the dome, and a plurality of series of reversely bent boiler tubes carried with each header and extending across the boiler, each series lying in the same plane, the boiler tubes of one header extending in the space between the groups of boiler tubes of adjacent headers on the opposite side.

10. In a steam generator or boiler, in combination, a water base, a steam dome, a plurality of spaced vertical circulating headers disposed along each side of the boiler and connecting the water base and the dome, and a plurality of series of U-shaped boiler tubes carried with each header and extending across the boiler, each series lying in the same vertical plane, the boiler tubes of one header extending in the space between the groups of boiler tubes of the adjacent headers on the opposite side, the tubes of one series being offset, vertically, with respect to the tubes of an adjacent series.

11. In a steam generator or boiler, in combination, a water base, a steam dome, a pair of spaced return pipes at each end of the boiler and in communication with the water base and steam dome, respectively, at least one pair of said return pipes being joined by a hollow wall also receiving the returning water.

12. In a steam generator or boiler in combination a rectangular water base, a rectangular steam dome, at least two return pipes, a hollow wall at least at one end of the boiler, said return pipes and hollow wall communicating with said water base and said steam dome to serve as return passages for the water and capable by themselves of supporting said steam dome.

13. In a steam generator or boiler, in combination, a water base, return pipes communicating therewith, a steam dome supported by and communicating with the return pipes, a plurality of vertical headers disposed along each side of the boiler, connections between the headers and the dome and water base, re-

spectively, a series of U-shaped boiler tubes whereof both legs are in open communication with each header and extending in substantially a horizontal direction and the boiler tubes being so disposed that one leg of a tube extending from one side lies in a vertical plane substantially passing between the legs of a tube extending from the opposite side.

14. In a steam generator or boiler, in combination, a water base, a steam dome, spaced return pipes carried by said water base and communicating with said water base and said steam dome and capable by themselves of supporting said steam dome, a plurality of vertical headers disposed between at least certain of said return pipes, fluid connections between the headers and the steam dome and water base, respectively, and boiler tubes carried with the respective headers.

15. In a steam generator or boiler, in combination, a water base, a steam dome, spaced return pipes carried by said water base and communicating with said water base and said steam dome and capable by themselves of supporting said steam dome, a plurality of independently removable vertical headers disposed between at least certain of said return pipes, fluid connections between the headers and the steam dome and water base, respectively, and boiler tubes carried with the respective headers.

16. In a steam generator or boiler the combination including a water base, a steam dome, return pipes connecting said water base and said steam dome capable by themselves of supporting said steam dome, a plurality of interchangeable removable vertical headers, severable connections between said headers and said water base, severable connections between said headers and said steam dome, and a series of substantially horizontally extending boiler tubes carried with each header, the boiler tubes of one header extending between the boiler tubes of the opposite header, the steam generated in each boiler tube passing directly into the header.

In testimony whereof I affix my signature.
WILLIAM A. MILLS.
